US00D870135S

(12) **United States Design Patent** (10) Patent No.: **US D870,135 S**
(45) Date of Patent: **** Dec. 17, 2019**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Cedric Kiefer**, Berlin (DE); **Henryk Wolllik**, Berlin (DE); **Jae Julien**, Seoul (KR); **Dae-Wung Kim**, Seoul (KR); **Jang-Won Seo**, Seoul (KR); **Ji-Hyun Lee**, Seoul (KR); **Yoo-Jin Choi**, Seoul (KR)

(73) Assignee: **SAMSUNG ELECTRONICS CO., LTD.**, Suwon-si (KR)

(**) Term: **15 Years**

(21) Appl. No.: **29/655,316**

(22) Filed: **Jul. 2, 2018**

(30) **Foreign Application Priority Data**

Jan. 5, 2018 (KR) 30-2018-0000878

(57)

CLAIM

The ornamental design for a display screen or portion thereof with graphical user interface, as shown and described.

DESCRIPTION

The FIGURE is a front view of a display screen or portion thereof with graphical user interface showing our new design.

The outer perimeter illustrated by dashed broken lines in the FIGURE illustrates a display screen or portion thereof and forms no part of the claimed design.
